(57) CLAIM

The ornamental design for a watch, as shown and described.

DESCRIPTION

FIG. 1 is a front and right side perspective view of a watch showing my new design;

FIG. 2 is a rear elevation thereof.

FIG. 3 is a rear and right side perspective view thereof.

FIG. 4 is a right side view watch thereof; and,

FIG. 5 is a front elevation thereof.

The broken line shown in FIGS. 1, 4, 5, 6 and 7 is for illustrative purposes only and does not form part of the claimed design.

1 Claim, 5 Drawing Sheets

FIG. 1

FIG. 2

FIG. 3

FIG. 4

FIG. 5
